UNITED STATES PATENT OFFICE

172,587

PUZZLE CHARM FOR A KEY CHAIN

Myron Fleishman, New York, N. Y., assignor to
Joseph Goodman, New York, N. Y.

Application January 21, 1953, Serial No. 23,202

Term of patent 3½ years

(Cl. D45—17)

To all whom it may concern:

Be it known that I, Myron Fleishman, a citizen of the United States and a resident of New York, in the county of Bronx, State of New York, have invented a new, original, and ornamental Design for a Puzzle Charm for a Key Chain, of which the following is a specification, reference being had to the accompanying drawing forming a part thereof.

On the drawing:

Fig. 1 is a top plan view of a puzzle charm for a key-chain;

Fig. 2 is a side elevational view thereof;

Fig. 3 is a front elevational view thereof;

Fig. 4 is a rear elevational view thereof; and
Fig. 5 is a perspective view thereof.

I claim:
The ornamental design for a puzzle charm
for a key chain, as shown.
